EXTENSION BAR FOR IRONING BOARDS

Bror E. Nilsson, Oceanside, N. Y.

Application November 27, 1939, Serial No. 306,367

2 Claims. (Cl. 38—106)

My invention relates to new and useful improvements in attachments for ironing boards.

An important object of my invention is the provision of a device that may be easily and expeditiously attached to an ironing board of standard design and construction.

Another object of my invention is the provision of an attachment for ironing boards which provides a frame that is unique in its construction to provide for adjustability both as to length and width, and that may be rocked about a horizontal axis to permit the frame to be supported at different angular positions relative to the said ironing board, all of said adjustments being capable of simultaneous performance upon actuation of a single control means to facilitate and expedite the proper positioning of the frame.

Still another object of my invention is the provision of an attachment for ironing boards wherein the adjustable features of the said frame permit the same to be extended to any desired length beyond the edge of the board for supporting an article to be ironed.

Yet another object of my invention is the provision of a device of the above-mentioned character that is particularly adapted to be used in conjunction with the ironing of lengthy articles such as curtains, sheets, and the like, and that will support the portions of the article that overhang the edges of the board while the same is being ironed.

A further object of my invention is the provision of an attachment of the above-mentioned character that is simple in construction, inexpensive to manufacture and efficient and efficacious in the performance of its duties.

Other objects and advantages of my invention will be apparent during the course of the following description.

In the drawing, forming a part of this specification, and in which like numerals are employed to designate like parts throughout the same,

Figure 1 is a fragmentary top plan view of an attachment embodying my invention, and showing the same associated with an ironing board.

Figure 2 is a side elevation of the same, and showing the frame, embodying a part of my invention, supported at different angular positions relative to the ironing board.

Figure 3 is a view similar to Figure 2, but showing the frame supported at different horizontal positions relative to the ironing board.

Figure 4 is a bottom plan view of my device,

Figure 5 is a vertical sectional view, taken on the line 5—5 of Figure 4.

Figure 6 is a vertical sectional view, taken on the line 6—6 of Figure 5.

5 Figure 7 is a top plan view of the supporting plates embodying a part of my invention,

Figure 8 is an end elevation of a modified form of the invention, and

Figure 9 is a top plan view of the clamping plates used in this form of the invention.

In the accompanying drawing, wherein for the purpose of illustration, is shown a preferred embodiment of my invention, the numerals 10 and 11 designate supports having a flat body portion 12 securely held to the underside of an ironing board 13 by means of screws 14, or the like. The body portion is formed at one end thereof with a depending flange 15 having a substantially square opening 16 therein adapted to accommodate the square shank portion 17 of the pin 18 which extends in spaced parallel relation with the underside of the board.

The clamping plates 19 and 20 are formed with right angularly disposed furrows 21 and 22, and 25 23 and 24, respectively, in close proximity to adjacent sides thereof. The furrow 22 of plate 19 is adapted to receive the upper portion of the pin 18 and the furrow 24 is adapted to receive the bottom portion of the pin in a manner to 30 position the plates 19 and 20 in superposed but slightly spaced relation. The plate 19 is formed with a tapped opening 25 and the plate 20 is formed with a drilled hole 26 registerable with the hole 25 in a manner whereby the thumb 35 screw 27 may be introduced therethrough to securely clamp the two plates together and to the pin 18.

The frame 28 includes a supporting rod 29 formed with a plurality of spaced openings 30 40 adjacent opposite ends thereof to receive the angularly disposed ends 31 of the supporting arms 32. The ends 33 of the arms are received within vertically registering furrows 21 and 23 in the plates 19 and 20 and extend transversely of the edge 34 of the ironing board, as illustrated in Figures 1 and 4. The supports 10 and 11 are preferably mounted adjacent opposite ends of the ironing board and the openings 30 in the rod 28 are provided to permit considerable adjustment in the positioning of the members 10 and 11 and to permit the same to be more readily attached to varying sizes of ironing boards.

When the thumb screw 27 is loosened, the arms 32 are readily slidable between the clamping plates 19 and 20 and may consequently be ex-

tended to any desired length beyond the edge 34 of the board for supporting an article to be ironed. When the rod 29 has been moved to the desired position the thumb screws may be tightened to securely hold the same against movement relative to the ironing board. As clearly illustrated in Figure 2, the clamping plates 19 and 20 may be rocked about the pin on a horizontal axis simultaneously with the adjustment of the arms to permit the rod 29 to be supported at different selected angular positions relative to the said board.

It may thus be seen that I have provided a means for adjusting the distance between the arms 32 in a manner permitting the frame 28 to be applied to varying sizes of ironing boards, and that an adjustable feature has been incorporated in the structure which permits the rod 29 to be positioned adjacent the edge 34 of the ironing board when not in use but wherein the rod may be extended to any desired length relative to the board when in use. In addition to the above features the frame is vertically rockable about a horizontal axis to support the rod 29 at different angular positions relative to the board.

Attention is now directed to Figures 8 and 9 where I have shown a modified form of the above described device.

In this form of the invention a clamping plate 40 of substantially rectangular formation in plan is formed with a furrow 41 extending across one face thereof adjacent the side 42. End openings 43 and 44 are countersunk to receive the heads 45 of screws 46 which hold the plate fixedly attached to the underside of the ironing board and in close proximity to the edge 34 thereof. A companion plate 47 is adapted to be positioned in superposed relation to the plate 40 and is formed with a furrow 48 in one face thereof and in spaced parallel relation with the side 49. The plate 40 is provided with a tapped hole 50 intermediate the end openings 43 and 44 and the plate 47 is formed with drilled hole 51 adapted to register with the opening 50 and to receive the threaded shank 52 of the thumb screw 53.

Clamping plates 40 and 47 are mounted at each end of the board and, when in the superposed position, the furrows 41 and 48 align vertically to receive the arms 32 of the frame 28. It is obvious that the thumb screw may be loosened to permit the frame to be extended to any desired length beyond the edge 34 of the board in the manner hereinabove described for the first form of the invention.

It is to be understood that the forms of my invention, herewith shown and described, are to be taken as preferred examples of the same, and that various changes in the size, shape and arrangement of parts may be resorted to without departing from the spirit of my invention, or the scope of the appended claims.

Having thus described my invention, I claim:

1. A rack support for use on an ironing board comprising a fixed bracket having a pivot, a frame including an arm extending transversely of the said pivot, and a clamp including cooperative plate elements adjustable relative to each other to grip the said pivot and arm therebetween, whereby movement of the plates away from each other will permit the arm to be simultaneously moved longitudinally and angularly to a selected position and whereby movement of the plates toward each other will cause the same to frictionally engage the pivot and arm to hold the frame in the said selected position.

2. A rack support for use on an ironing board comprising a fixed bracket having a pivot, a frame including an arm extending transversely of the said pivot, a clamp including cooperative plate elements arranged at opposite sides of the pivot and arm, and a single control means for moving the plates relative to each other, whereby movement of the plates away from each other will permit the arm to be simultaneously moved longitudinally and angularly to a selected position and whereby movement of the plates toward each other to frictionally engage the pivot and arm will hold the frame in the said selected position.

BROR E. NILSSON.
